(57) **CLAIM**

The ornamental design for a suction coagulator, as shown and described.

DESCRIPTION

FIG. 1 is a first perspective view of a suction coagulator showing our new design;

FIG. 2 is a rear elevation view of the suction coagulator;

FIG. 3 is a front elevation view of the suction coagulator;

FIG. 4 is a right elevation view of the suction coagulator;

FIG. 5 is a left elevation view of the suction coagulator;

FIG. 6 is a top plan view of the suction coagulator; and,

FIG. 7 is a bottom plan view of the suction coagulator.

The broken lines shown in the figures represent portions of the suction coagulator that form no part of the claimed design.
